UNITED STATES PATENT OFFICE.

RICHARD H. MOORE, OF WAKITA, OKLAHOMA.

GRIPPER-DISK FOR BINDERS.

1,169,989.

Specification of Letters Patent.

Patented Feb. 1, 1916.

Application filed November 17, 1914. Serial No. 872,604.

To all whom it may concern:

Be it known that I, RICHARD H. MOORE, a citizen of the United States, residing at Wakita, in the county of Grant and State 5 of Oklahoma, have invented a new and useful Gripper-Disk for Binders, of which the following is a specification.

The present invention appertains to knotting mechanisms for binders, and more particularly to a twine gripper or holder.

With the customary twine gripper or holder now employed in the knotting mechanisms of binders, the notches of the disk become rounded and smooth due to the wear 15 and friction after continued use, which not infrequently renders the gripper inefficient or inoperative, since the twine hook will not properly hold the twine in the notches of the disk.

20 This invention contemplates the provision of a twine gripper or holder so formed, as to continue in its efficiency, notwithstanding the fact that the gripper becomes worn away in the continued use to which it is subjected, and whereby the common grippers or 25 holders may be readily altered in accordance with the present invention, to increase the life and efficiency thereof.

It is also within the scope of the invention, to provide simple and inexpensive means for increasing the life and efficiency of the gripper or holder, which will be thoroughly practical in use.

With the foregoing and other objects in view, the present invention resides in the peculiar formation of the gripper or holder disk for the twine, as hereinafter set forth in detail.

The invention is illustrated in the accompanying drawing, wherein:—

Figure 1 is an elevation of one side of the gripper or holder. Fig. 2 is an elevation of the other side thereof. Fig. 3 is an enlarged sectional detail taken on the line 45 3—3 of Fig. 1.

The twine gripper or holder embodies the companion or complementary disks 1 and 2, which are secured together in the usual manner, and each of which is provided with

a series of peripheral notches 3, coinciding 50 or registering with the notches of the opposite disk for cooperation with the usual twine hook (not shown).

In carrying out the present invention, the outer side of each of the disks 1 and 2 is 55 beveled around each notch 3, as at 4, and the beveled edge 4 of each notch is provided with a series of oblique grooves 5 forming the serrated edges 6 for the notches 3. The bevels 4 extend from the outer sides of 60 the disks to the inner sides thereof, and the grooves 5 extend to the edges of the bevels.

With the provision of the peculiar bevels and grooves it has been found in practice, that notwithstanding the fact that the 65 notches having the serrated edges become worn due to the continued friction to which they are subjected, they will always effectively receive and hold the twine. In this manner, the life and efficiency of the gripper is materially enhanced, it being a frequent occurrence with the ordinary gripper or holder, for the same to become worn out and inefficient within a short period due to the rounding and smoothing of the twine 75 notches.

Having thus described the invention, what is claimed as new is:—

A twine gripper for binders embodying a pair of parallel spaced disks secured together, the peripheries of the disks having coinciding curved notches, the outer sides of the disks being beveled around each notch, the bevels extending to both ends of the notches and extending from the outer 80 sides to the inner sides of the disks, each bevel being provided from end to end with a series of grooves extending to the edges of the bevel, and said grooves being arranged obliquely. 85

In testimony that I claim the foregoing as my own, I have hereto affixed my signature in the presence of two witnesses.

RICHARD H. MOORE.

Witnesses:

LOUIS M. BERT,
GRACE M. GARRETT.
